Primary Examiner — Robert M Spear*Assistant Examiner* — Marissa J Cash(57) **CLAIM**

The ornamental design for a trocar, as shown and described.

DESCRIPTION

FIG. 1 is a perspective view of an embodiment of a trocar of the present application, showing a trocar and an insert; FIG. 2 is a right side elevational view of the trocar of FIG. 1;

FIG. 3 is a left side elevational view of the trocar of FIG. 1;

FIG. 4 is a top elevational view of the trocar of FIG. 1;

FIG. 5 is a bottom elevational view of the trocar of FIG. 1;

FIG. 6 is a rear elevational view of the trocar of FIG. 1; and,

FIG. 7 is a front elevational view of the trocar of FIG. 1.

The broken lines shown in FIGS. 1 and 6 depict environmental subject matter only and form no part of the claimed design.

1 Claim, 4 Drawing Sheets(56)
